H. G. COOPER

Des. 156,607

CANNED GOODS DISPLAY RACK OR SIMILAR ARTICLE

Filed April 12, 1948

FIG. 3

INVENTOR
HAROLD G. COOPER
BY Milton W. Lee
AGENT

UNITED STATES PATENT OFFICE

156,607

CANNED GOODS DISPLAY RACK OR SIMILAR ARTICLE

Harold G. Cooper, Los Angeles, Calif., assignor to Union Oil Company of California, Los Angeles,
Calif., a corporation of California

Application April 12, 1948, Serial No. 145,657

Term of patent 7 years

(Cl. D80—9)

To all whom it may concern:

Be it known that I, Harold G. Cooper, citizen of the United States and residing at 2239 Glendon Avenue, Los Angeles 25, Los Angeles County, California, have invented a new, original, and ornamental Design for a Canned Goods Display Rack or Similar Article, of which the following is a specification, reference being had to the drawing, forming part thereof.

Fig. 1 is a front elevation of a canned goods display rack showing my new design;

I claim:

The ornamental design for a canned goods display rack or similar article, substantially as shown.

HAROLD G. COOPER.
